UNITED STATES PATENT OFFICE.

AUGUSTUS ALBERT WEST, OF BROOKLYN, NEW YORK.

TYPE-WRITER.

1,163,725.

Specification of Letters Patent. Patented Dec. 14, 1915.

Application filed March 22, 1911. Serial No. 616,196.

To all whom it may concern:

Be it known that I, AUGUSTUS ALBERT WEST, a citizen of the United States, and resident of the borough of Brooklyn, county 5 of Kings, city and State of New York, have invented certain new and useful Improvements in Type-Writers, of which the following is a specification.

The device, the subject of this application 10 while properly termed an improvement in typewriters is intended more especially as an improvement in the key lever operating mechanism and the type bar, and although certain other improvements are noticeable 15 it is my intention to make them the subject of additional applications and to that end I have executed an application for United States Letters Patent for an improvement in paper rollers or platens and the carriage 20 upon which the roller is mounted, which application bears the date of March 22d, 1911, Serial #616,195.

My observation has satisfied me that much improvement can be made in the mechanism 25 that operates the type bars, not only with a view to simplify the structure but also to increase its efficiency along certain lines. I have discovered that a certain improved power transmitting means may be employed 30 that although not requiring a longer or more powerful depression of the key will nevertheless produce a more powerful stroke of the characters, which will be found especially useful in certain classes of work.

35 The following is what I consider the best means of carrying out this invention.

The accompanying drawings form a part 40 of this specification, in which—

Figure 1 is a view in side elevation partly 45 in section, in this view as in many of the others, the operating mechanism of but one key and type bar is shown. Fig. 2 is a plan view. This view is not complete, the remaining parts being duplicates of the parts 50 shown. Fig. 3 is a view in perspective, of an assembled typewriter into which my improvements have been incorporated. Fig. 4 and the remaining figures are on a larger scale, they show a single key and type bar 55 operating mechanisms and the parts adjacent thereto. Figs. 4 and 5 are in side elevation, partly in section. Figs. 6 and 7 are in plan, and Figs. 8 and 9 are in side elevation, and show the striking mechanism in two different positions during its operation.

Similar reference characters indicate like parts in all the figures where they appear.

Referring to Fig. 3, it will be seen that I have indicated all of the keys and the bars by which they are supported by the reference numerals 1 to 28 and 1^a to 28^a respectively, and as these members are in duplicate I choose to describe one only and have chosen one that is shown arranged near the center of the group and indicated by 15.

65

Now referring to the figures in which the details of construction are shown, 15 indicates the key arranged to receive the pressure from the finger of the operator and 15^a the standard upon which the key is supported. 70 A bar 15^b, which I may term a lever bar supports the standard 15^a. This bar is in turn supported by the pivot 15^c, which passes through a hole provided for it near one end of the bar 15^b. This arrangement 75 divides the bar 15^b up into two unequal parts, and secured to the shorter part of the bar is the coiled spring 15^e, which operates to depress that end and thus elevate the long 80 inwardly extending end of the bar. The lower end of the spring 15^e is secured to any convenient point on the base of the machine, and the upper end is adjustably secured to an adjusting screw 15^f arranged in the short 85 end of the lever bar 15^b. The spring 15^e and screw 15^f operate to limit the movement of the lever 15^b.

80

The type bars are indicated at 15^d. Each is bent at a right angle at a point less than mid-length of the bar. The shorter portion 90 of the type bar 15^d carries the printing characters and although I have shown but three characters on each bar this number may be increased or otherwise varied. The longer part of the bar is supported in the brackets 95 B, of which there are two, one arranged adjacent to the right angle bend in the bar 15^d and the other supporting the outwardly extending longer end. A spring 15^g arranged upon the longer section of the bar 15^d and 100 adjacent to one of the brackets B will be described when the operation of the whole device is set forth.

100

Pivotedly secured to the inner or longer part of the bar 15^b, and not far from the end thereof is the sub-lever or latch member 15^g secured upon the pivot 15^c and held normally in a nearly vertical position by the spring 15^g. The member 15^g is pivoted quite 105 near its center and the lower end is rounded 110

so that when the depression of the key 15 forces downward the inner end of the rod 15^b and the parts carried thereby, the rounded end of the latch member 15^e will 5 contact with the upper side of the sub-base C and be forced rearward thus causing the member 15^e to rock or partly rotate on its bearing pivot 15^a.

A pivot 15^m arranged near the upper end 10 of the member 15^e supports the link 15°, which connects the arm 15^t to the latch 15^e and a pivot 15^h provides a loose but secure connection between the arm 15^t and the link 15°. The arm 15^t is secured to the type bar 15^d and any motion of the arm 15^t will be 15 accompanied by a like motion in the type bar, and an adjusting screw 15^g supported by the casing 33, and having the slotted head 15° and the lock nut 15^p has its lower 20 end arranged adjacent to the arm 15^t and adjustably limits the extent of the upward travel of the arm 15^t, thus regulating the amount of travel of the type-bar.

Arranged adjacent to the inner end of the 25 bar 15^b and pivotally supported by the brackets 15^j and 15^k I have arranged the longitudinally slotted member 15^l, the slot of which accommodates the horizontal portion 30 of the type bar 15^d, and secured to the type bar and in constant bearing with the upwardly extending ends of the member 15^l, I have arranged the collar 15^l. The member 15^l is held at an angle, the lower end extending inward toward the center of the 35 machine, and the upper end outward. Downward pressure on the bar 15^b rocks the member 15^l by forcing outward the lower end thereof, and the upper end which is forced in carries with it the collar 15^l 40 and advances the character carrying end of the type bar 15^d to the center line. It is obvious that this construction being duplicated on each of the keys 1, 2, 3, etc., or arranged in operable relation therewith, 45 each of the type bars will upon the depression of the key to which it is connected advance to a common center. The latch member will then come in contact with the sub-base C and through the links 15° and 50 rods 15^t be rotated through an arc and be caused to strike a conveniently arranged platen or a paper carried thereby. The operation of the member 15^l is clearly shown in Figs. 4 and 5, and the operation of the 55 members 15^e, 15^t, 15°, etc., are shown in Figs. 8 and 9.

A spacing bar 30 supported by the pins 30^a and 30^b is shown arranged across in front of the keys and the shift keys 31 and 60 32, supported by the vertical bars 31^a and 32^a are shown at the left of the key bank. All of these members are described in detail in another application dated March 22nd, 1911, Serial #616,195.

65 The cover 33 having the upwardly ex-

tending and centrally disposed chamber 34 and perforated to accommodate the many operating parts may be of sheet iron enamored, and the base *d* may be a casting. I have so constructed them and I prefer the 70 whole as shown and described.

So that the action of the whole device may be more readily understood I will add a short description of the action using the reference characters in conjunction with the 75 names of each of the parts.

The operator pressing with the finger on the key 15, forces down the standard 15^a, and the bar 15^b against the pull of the spring 15^c. The member 15^e pivoted at 15^m 80 to the bar 15^b is carried down until its lower end strikes the base C at which time the member 15^e is rocked on its pivot and pulling the link 15^o partially rotates the type bar 15^d and causes the character carrying 85 part to strike the platen. Before the member 15^e has reached the base C, the member 15^t has been oscillated by having its lower end pushed backward by the bar 15^b, and the upper end thus caused to advance pushes 90 against the collar 15^l and brings the type bar 15^b into the center or striking line. Releasing the pressure on the key 15 allows all of the parts to be restored to their normal position by reason of the springs connected 95 thereto. The bar 15^b is restored by the spring 15^c, the member 15^e is brought to a nearly perpendicular position by the spring 15^s and the type bar 15^d is withdrawn from the center line by the spring 15^t.

100 This arrangement and construction has a number of advantages among which are the short and powerful downward stroke, the visible writing line, and the low arrangement of the platen which results in the production of a machine of a very small size.

105 Modifications may be made within the scope of the appended claims without departing from the principle or sacrificing the advantages of this invention. It is possible that some of the springs may be omitted, and it is possible that a somewhat modified structure may be designed. Other modifications may be made by a good mechanic.

Having carefully and fully described my 115 invention what I claim and desire to secure by Letters Patent is:

1. In a typewriter, a lever member, a type-bar adapted to be moved toward the platen by said lever member, a centrally pivoted 120 forked member straddling said type-bar and adapted to be oscillated by said lever member for reciprocating said type-bar laterally, and a guide arranged adjacent to said forked member, said guide being adapted to support the said lever member against displacement by the said forked member as herein specified.

125 2. In a typewriter, a lever member, a type-bar moved toward the platen by said lever 130

member, a centrally pivoted forked member straddling said type-bar and adapted to be oscillated by said lever member for advancing said type-bar laterally and a spring arranged upon said type-bar for restoring said type-bar after each lateral displacement as specified.

3. In a typewriter a lever member, a sub-lever having its free end smoothly rounded pivoted to said lever member, and a spring between the free end of said sub-lever and the first said lever member, a type bar rotatably arranged adjacent to said lever member, and a link between said type bar and said sub-lever, and means for depressing said lever member and operating the parts connected thereto as specified.

4. In a typewriter, a lever member, a type bar moved toward the platen by said lever member, and a centrally pivoted forked member straddling said type bar and adapted to be oscillated by said lever member for reciprocating said type bar laterally as specified.

5. In a typewriter, a key, a lever supporting said key and operated by and pivoted below said key, a type bar pivoted to and operated

by said lever, adjustable means for applying a tension in opposition to the downward movement of said key and an adjustable screw arranged adjacent to said type bar for limiting the extent of the upward movement of said type bar as herein specified.

6. In a typewriter, a key, a lever member pivotally supported below and connected to said key, a rotatable member secured to said lever member at substantially right angles thereto, and having one of its ends rounded, a type bar arranged adjacent to said rotatable member and free to revolve and reciprocate, a crank carried by said type bar, and a link connecting said crank with said rotatable member, in combination with a centrally pivoted fork and a collar fixed upon said type bar arranged adjacent to said lever member for reciprocating said type bar prior to its rotation.

Signed at New York city, county and State of New York this 21 day of March 1911 in the presence of two witnesses.

AUGUSTUS ALBERT WEST.
